UNITED STATES PATENT OFFICE.

NICLA COLOMYJCZUK, OF SOUTH PORCUPINE, ONTARIO, CANADA.

ORDNANCE.

1,217,415.

Specification of Letters Patent. Patented Feb. 27, 1917.

Application filed September 5, 1916. Serial No. 118,560.

To all whom it may concern:

Be it known that I, NICLA COLOMYJCZUK, a subject of the Emperor of Austria-Hungary, residing at South Porcupine, in the 5 Province of Ontario and Dominion of Canada, have invented certain new and useful Improvements in Ordnance, of which the following is a specification.

This invention relates to certain new and 10 useful improvements in ordnance.

The primary object of this invention is the provision of cannon adapted for hurling an unfolding missile in a substantially horizontal direction whereby a large area may 15 be covered at a single discharge of the device during its operation.

A further object of the device is the provision of a cannon having two shooting bores whereby separate missiles are hurled 20 forward together with a connector adapted for unfolding during the diverging path of travel of the said missiles.

A still further object of the device is the provision of a cannon having diverging 25 bores for divergently projecting missiles while a normally folded connector is carried by the said missiles adapted to be forwardly assisted by means of an auxiliary firing chamber.

30 In the drawings forming a part of this application and in which like designating characters refer to corresponding parts throughout the several views:

Figure 1 is a central longitudinal sectional view of the device.

Fig. 2 is an enlarged elevational view of the muzzle end of the gun.

Fig. 3 is a transverse sectional view taken upon line III—III of Fig. 1.

40 Fig. 4 is a central longitudinal sectional view through a slightly modified form of the device, a portion of the gun being shown in side elevation.

Fig. 5 is a side elevation of one of the 45 missiles employed with the device.

Fig. 6 is a view of the same partly in longitudinal section with the collar broken away and partially assembled, and,

Fig. 7 is a side elevation of one of the 50 missiles substantially of the form employed with the modified device illustrated in Fig. 4.

The present device contemplates a cannon

10 having a powder chamber 11 and any desirable form of breech block 12 adapted 55 for igniting the powder or explosive 13 arranged within the said chamber. An oval-shaped recess 14 is provided in the forward end 15 of the gun while two forwardly diverging bores 16 communicate between the 60 said chamber 11 and recess 14.

Missiles 17 of a desirable form such as that illustrated in Fig. 5 of the drawings are positioned within the outer open ends of the bores 16 within the recess 14, the same 65 being adapted to be projected forwardly by means of projectiles 18 arranged within the rear ends of the bore 16 adjacent the explosive 13. A connecting wire or cable 19 is normally arranged within a depression 70 20 in the bottom of the recess 14 and between the open ends of the bore 16, the said cable having its opposite ends attached to the missiles 17 by means of collars 21 carried by the missiles. An auxiliary chamber 22 75 is provided at the bottom of the depression 20 having communication by means of a central axial bore 23 with the chamber 11. A disk or plate 24 is preferably arranged over the auxiliary chamber 22 between the 80 powder 25 arranged therein and the folded member 19. The cannon 10 is preferably arranged with ground wheels 26.

From this detailed description of the device it will be understood that the gun is 85 loaded for operation as illustrated in Fig. 1, the missiles 17 being forced into the ends of the bore 16 and the connector 19 wedgely retained within the depression 20. Upon igniting the charge 13 the projectiles 90 18 will be fired through the bores 16, striking the missiles 17 and seating the reduced forward ends 27 of the projectiles within the central recess 28 of the missiles. The projectiles and missiles are thereby united both 95 moving forwardly upon diverging lines carrying the connector 19 therewith unfolding during the constant separation of the said missiles. The firing of the explosive 15 is communicated through the bore 23 for exploding the explosive 25 within the auxiliary chamber 22 whereby the disk 24 is projected exerting further impelling force upon the connector 19. The inter-engagement between the projectiles 18 and missiles 100 17 may be omitted if desired in which event 105

the impact of said projectiles upon the missiles is sufficient to impel the latter forwardly. The gun 10 being arranged substantially horizontal and upon a line with the enemy, the missiles 17 and connector 19 will form a manner of death-dealing member of considerable length.

When the form of the device illustrated in Fig. 4, the cannon 29 is provided with a firing chamber 30 provided with an explosive 31 adapted for ignition by any means such as a fuse member 32, the said cannon having forwardly diverging bores 33 connecting the chamber 30 with a recess 34 in the muzzle thereof. Missiles 40 of the form best illustrated in Fig. 7 of the drawings are seated within the forward ends of the bores 33 while a connecting chain 41 is arranged between the two missiles 40, being attached to the collars 42 thereof. Projectiles 43 are arranged in the rear ends of the bores 33 and upon the exploding of the charge 31, the said projectiles 43 are forced through the bores 33 striking the missiles 40 and carrying the same forwardly in diverging directions while the chain 41 unfolds to its outstretched arrangement during the course of flight of the said missiles. The aforesaid missile 17 is illustrated in Figs. 5 and 6 of the drawings as having a pointed forward end 36 and is adapted for mounting the rubber ring 21 thereon to which a connecting chain 35 may be attached, the missile 17 having the said axial bore 28. The rubber collar 21 is provided with a depending flange 36 adapted for seating within an annular socket 37 in the shoulder 38 of the missile 17 when the ring is forced downwardly thereover and seated upon the reduced cylindrical forward end portion 39 thereof, the connecting member being readily attached in this manner to the missiles when desired.

It will be seen that a serviceable gun is arranged which having only two firing bores is adapted for projecting a combined missile with the killing properties of many times that number of missiles.

What I claim as new is:—

1. A cannon having divergent bores, an explosive discharging chamber at the converging ends of the said bores, missiles operatively arranged within the said bores, a foldable elongated connector secured to the said missiles, a disk upon which the said connector is positioned, the said gun having an auxiliary explosion chamber beneath the said disk and provided with an auxiliary bore connecting the said chambers whereby the explosive within the said chambers is fired substantially simultaneously upon the operation of the device.
2. A cannon having an explosive chamber at the breech end thereof and a trans-

verse recess at its muzzle end, and with forwardly diverging bores connecting the said chamber and recess, the muzzle of the gun being further provided with a depression between the said bores, projectiles in the rear ends of the said bores, missiles fitted within the forward ends of the bores, and a flexible metallic connector secured to the said missiles and normally arranged in folded position within the said depression.

3. A cannon having an explosive chamber at the breech end thereof and a transverse recess at its muzzle end and with forwardly diverging bores connecting the said chamber and recess, the muzzle of the gun being further provided with a depression between the said bores, projectiles in the rear ends of the said bores, missiles fitted within the forward ends of the bores, and a flexible metallic connector secured to the said missiles and normally arranged in folded position within the said depression, the said projectiles having reduced forward ends, the said missiles having axial recesses adapted for the engaging reception with the adjacent ends of the said projectiles when the gun is fired.

4. A cannon having an explosive chamber at the breech end thereof and a transverse recess at its muzzle end and with forwardly diverging bores connecting the said chamber and recess, the muzzle of the gun being further provided with a depression between the said bores, projectiles in the rear ends of the said bores, missiles fitted within the forward ends of the bores, a flexible metallic connector secured to the said missiles and normally arranged in folded position within the said depression, the said gun being provided with an auxiliary chamber having explosive opening into the said depression and having an axial bore connecting the said auxiliary chamber and the breech chamber, and a disk between the said auxiliary chamber and flexible connector whereby a forward impulse is exerted upon the said missiles and its connector substantially simultaneously during the firing of the gun.

5. A cannon having an explosive chamber at the breech end thereof and a transverse recess at its muzzle end and with forwardly diverging bores connecting the said chamber and recess, the muzzle of the gun being further provided with a depression between the said bores, projectiles in the rear ends of the said bores, missiles fitted within the forward ends of the bores, and a flexible metallic connector secured to the said missiles and normally arranged in folded position within the said depression, the said projectiles having reduced forward ends, the said missiles having axial recesses adapted for the engaging reception with the

adjacent ends of the said projectiles when the gun is fired, the said gun being provided with an auxiliary chamber having explosive opening into the said depression and 5 having an axial bore connecting the said auxiliary chamber and the breech chamber, and a disk between the said auxiliary cham-

ber and flexible connector whereby a forward impulse is exerted upon the said missiles and its connector substantially simultaneously during the firing of the gun. 10

In testimony whereof I affix my signature.

NICLA COLOMYJCZUK.
